BRAKE CHAIN ATTACHING DEVICE

Original Filed Dec. 10, 1930

UNITED STATES PATENT OFFICE

JACK WILSON, OF CHICAGO, ILLINOIS, ASSIGNOR TO UNIVERSAL DRAFT GEAR ATTACHMENT CO., OF CHICAGO, ILLINOIS, A CORPORATION OF ILLINOIS

BRAKE CHAIN ATTACHING DEVICE

Refiled for abandoned application Serial No. 501,231, filed December 10, 1930. This application filed January 22, 1932. Serial No. 588,093.

The invention relates to the hand operating mechanism of railway cars and brakes, and more particularly to the means for attaching the brake chain to the winding drum.

5 This application is refiled for abandoned application Ser. No. 501,231, filed Dec. 10, 1930.

10 The object of the invention is to provide means for anchoring the chain to the drum, whereby the use of an attaching draft pin is avoided; and it consists of the structure such as hereinafter described, and as illustrated in the accompanying drawing, in which,

15 Fig. 1 is a detail end elevation of a railway car end and of the brake operating mechanism secured thereto;

Fig. 2 is a detail sectional view on an enlarged scale, taken on the line 2—2 of Fig. 1;

20 Fig. 3 is a view on the line 3—3 of Fig. 2;

Fig. 4 is a detail of the winding drum and brake chain, taken on the line 4—4 of Fig. 3; and

25 Fig. 5 is a sectional detail similar to Fig. 4, showing a modified form of construction:

The invention is especially applicable to so-called high power brakes, in which the winding drum makes but a single rotation in the brake-setting operation and is in the form 30 of an eccentric, the chain being attached at its longest radius in order that the slack may be quickly taken up, the power applied being increased as the drum is turned.

Heretofore it has been the practice to attach the chain to the drum by inserting the end link in a periphery recess and setting a pin directly through the drum, passing it through the link. This method of attachment is objectionable mainly because it weakens the drum, requires the use of a special part, and increases the labor necessary in connecting and disconnecting the chain. According to the present invention a pocket of special form is provided within the periphery of the drum, within which the end link of the chain is seated; a channel leading from the pocket accommodating the second link, the plane of which is transverse to that of the first link.

50 In the drawing the end of a car is indi-

cated at 10, to which the casing 11, carrying the brake operating mechanism, is suitably attached. This mechanism comprises a brake staff 12, extending horizontally through the casing and carrying a hand wheel 13 and a pinion 14. This pinion meshes with a gear wheel 15, of much larger diameter, which is similarly journaled at 16 in the casing walls.

55 The winding drum 17 is fixed upon the shaft of the gear 15, or may be formed integrally therewith. This drum is in the form of an eccentric cam, and preferably has a plurality of flat faces, as shown at 18, 19, 20 and 21, and is circumferentially channelled, as shown at 22, to receive the chain links, the planes of which are transverse to the axis of the drum.

60 Within the body of the cam, and intermediate of its faces 18 and 21, there is formed a pocket 23, opening through the periphery of the cam and of such size as to receive the end link 24 of the chain with its plane parallel to the axis of the cam, one end of this pocket forming a shoulder 25 for sustaining the stresses of draft applied to the link 24. The peripheral slot 22 of the cam extends through this shoulder into the pocket 23, to accommodate the second link 26 of the chain.

65 The axial dimension of the drum is necessarily restricted, and consequently, in order to avoid weakening of the drum, the pocket 23 is so shaped that one link 24, is housed therein, its longitudinal axis being oblique to the drum axis. A pin 27 is inserted transversely through the cam, across the throat of the pocket 23, for the purpose of preventing accidental dislodgment of the link 24 therefrom.

70 As the cam 17 is turned in counter-clockwise direction for winding up the chain the link 26 will be received in the channel 22, extending along the drum face 18, the next successive link of the chain lying flatly along the face 19, the following link being received in the channel along the face 20, and the following link lying flatly along the face 21.

75 As shown in Fig. 5, there may be substituted for the end link 24 a half link 28, and in this case the size of the receiving pocket

29 may be reduced, suitable means being provided for preventing the accidental shifting of the half link. For this purpose the retaining pin 30 may be so positioned as to 5 engage one end of the half link, a shoulder 31 formed within the pocket being engaged by its opposite end. This modification has the advantage that the walls of the drum are weakened to a less extent while it is less desirable than the previously described construction, in that it requires the cutting of the link of the chain or the provision of an extra half link.

I claim as my invention—

15 1. A winding drum for car brakes having a pocket entering from its periphery for receiving an end link of a chain, and a slotted shoulder at the base of the pocket for resisting strain on the named link and 20 accommodating the next adjacent chain link.

2. A winding drum for car brakes having a pocket entering from its periphery and shaped to receive the end link of a chain when positioned with its major axis oblique 25 to the axis of the drum, and a shoulder for resisting pulling strain on the named link, such shoulder being slotted to accommodate the next adjacent link of the chain.

3. A winding drum for car brakes having a pocket entering from its periphery for receiving a holding bar positioned oblique to the axis of the drum, and a slotted shoulder at the forward side of the pocket for accommodating a chain link when looped upon 35 the bar.

In testimony whereof I affix my signature.

JACK WILSON.
